UNITED STATES PATENT OFFICE.

MATHIAS BLAHA, OF BERLIN-LICHTENBERG, GERMANY.

DETACHABLE TUBE-JOINT.

1,086,312.

Specification of Letters Patent.

Patented Feb. 3, 1914.

Application filed March 18, 1913. Serial No. 755,226.

To all whom it may concern:

Be it known that I, MATHIAS BLAHA, carpenter, a subject of the King of Bavaria, in the German Empire, residing at Berlin-
5 Lichtenberg, in the Kingdom of Prussia, in the German Empire, have invented certain new and useful Improvements in Detachable Tube-Joints; and I do hereby declare the following to be a full, clear, and
10 exact description of the invention, such as will enable others skilled in the art to which it appertains to make and use the same.

This invention relates to detachable tube joints, and has for an object to provide a
15 joint especially adapted for the frameworks of air craft, and the like, and the invention contemplates the provision of a joint which will be readily united and detached, and which, when in position, will form a strong
20 and effective union.

It is another object of my invention to provide a detachable tube joint which will be simple, and constituted of a minimum number of parts.

25 In the accompanying drawings forming a part of this application, and in which similar reference symbols indicate corresponding parts in the several views:—Figure 1 is an elevational view, partly in section, of the members of the joint detached; and Fig. 2 is a sectional view of the members united.

Referring more particularly to the drawings, *a* and *e* designate the ends of two tubes
35 to be joined, the latter of which is provided, in spaced relation to its end, with an annular groove *d*, preferably formed by displacing the material of the tube radially inward, whereby to provide a corresponding
40 annular bead *h* projecting into the interior of the tube. The tube *e* is further slotted, as at *c*, for a distance from its end to admit of expansion and contraction in receiving the tube *a* which is of a diameter to snugly
45 fit within the same, and is provided with a groove *b* at a suitable distance from its end to accommodate the bead *h* when the two tubes are inter-fitted.

The groove *b* may be formed in a manner
50 similar to that described of *d* above, and as will more clearly appear from an inspection of Fig. 2.

A sleeve *f* is slidable on the tube *e*, and is provided, preferably midway of its ends, with a perforation through which projects 55 a finger *g* carried on the free end of a flat spring *i* secured upon the exterior face of the sleeve. The finger *g* is adapted to occupy the groove *d* in the tube *e* when the former has been moved to the position shown 60 in Fig. 2, when contraction of the tube *e* is effected to prevent longitudinal withdrawal of the tubes, and to prevent accidental displacement of the sleeve *f*.

In assembling the joint, the tube *a* is fitted 70 in the tube *e*, the end of the former striking the bead *h*, and thereby causing an expansion of the outer tube through the slot *c* until the groove *b* arrives in registry with the said bead, whereupon the tube *e* will contract thereabout due to the inherent stress 75 of the material. The sleeve *f* is now moved to the position shown in Fig. 2, positively preventing accidental expansion of the sleeve and is automatically locked in position by 75 the finger *g*. The detachment of the joint may be effected by prying up the flat spring *i* and moving the sleeve *f* on the tube *e*, when it will be seen the tubes may readily be separated. 80

I have illustrated and described preferred and satisfactory construction, but changes could be made within the spirit and scope of my invention.

I claim:—

85 In a detachable tube joint, the combination of two tubes having the ends thereof fitted within one another and provided with a complementary bead and groove to prevent longitudinal withdrawal of the tubes, 90 the outer tube being slotted to admit of expansion and contraction and provided with an external annular groove, and a sleeve slidable on said tube and provided with a spring-pressed finger adapted to occupy the 95 groove formed on said tube, whereby to prevent accidental displacement of the parts.

In testimony whereof, I have affixed my signature, in presence of two witnesses.

MATHIAS BLAHA.

Witnesses:
